UNITED STATES PATENT OFFICE.

MILTON B. REACH, OF SPRINGFIELD, MASSACHUSETTS, ASSIGNOR TO A. G. SPALDING & BROS., OF NEW YORK, N. Y., A CORPORATION OF NEW JERSEY.

TENNIS RACKET.

Application filed July 12, 1927. Serial No. 205,115.

My said invention relates to improvements in tennis rackets of the open throat wood frame type. The tendency under modern fast play conditions is towards a lighter racket which the open throat secures, but the additional flexibility imparted thereby to the throat of the racket and the additional torque taking place in the handle tend to open up the glued joints and develop splits 10 in the flake.

The present invention aims to provide a construction which will be free from these objections, and it includes the novel features of construction hereinafter described and 15 defined by the appended claims.

In order that the invention may be more readily understood, reference is made to the accompanying drawings, in which:—

Figure 1 is a plan view of a racket frame 20 as it appears at one stage of manufacture.

Fig. 2 is a similar view of the completed article, partly broken away.

Fig. 2^a is a section on line 2^a—2^a of Fig. 2.

Fig. 3 is a section on line 3—3 of Fig. 1.

Fig. 4 is an enlarged section on line 4—4 of Fig. 1, partly broken away.

Fig. 5 is a view of a modification.

Figs. 6 and 7 are enlarged detail views 30 showing two forms of flake termini.

Fig. 8 is a view of a further modification.

Referring by reference characters to this drawing, the numeral 1 designates the bow, made up in the usual manner by bending an ash strip to bow shape with the ends 1^a jux-

35 tapered and glued together to form the handle portion, which may be shaped and finished in the ordinary or any desired manner.

To complete the oval or head portion of 40 the racket a crescent shaped strip 2 is secured to the bow, extending across the throat. The space left between such strip

45 and the portions 1^b of the bow where they leave the strip and merge into the handle has in general practice been filled with a throat piece in the shape of a solid block, glued to the bow member and crescent shaped strip, as attempts to construct a racket without such throat piece have re-

50 sulted in an article which would not stand the strain of the stringing, hence necessitating the retention of the throat piece with its additional weight and the ensuing undesirable rigidity at this point.

55 In the present construction I provide the

outside face of the crescent shaped strip 2 with a part or supplemental member 3 curved to conform to the curvature of the arc-shaped strip, and having its ends beveled to conform to the incline of the portions 1^b. 60

Said member 3 is glued to the outer face of the crescent shaped strip 2 and its ends are glued to the inside faces of the portions 1^b. 65

The stringing 4 at this point passes through both the member 2 and supplemental or reinforcing member 3, and thus ample support is provided for the stringing, while at the same time an open throat is 70 provided in rear of the member 3 which lightens the racket and also reduces rigidity at this point.

The joints between the members 2 and 3 and the adjacent bow parts are covered by 75 the surfacing and finishing strips 5 which completely overlie these parts and are glued thereto, and these impart additional bracing effect. The strips 2 and 3 where they cross the throat are of such proportions that the 80 aggregate thickness at this point is substantially the same as the side portions at the base of the bow.

Instead of making the part 3 as a separate member glued to the part 2, it may be 85 made integral therewith as shown at 2^a, 3^a, Fig. 5, by making the crescent shaped strip of thicker material and shaping it down to the form shown in said figure.

I have found that the tendency of the 90 glued joint between the handle sections 1^a which are of ash, to open up, which occurs when these are glued directly together, may be avoided by interposing therebetween a filler piece 1^c of soft wood, as shown in Fig. 95 1, to opposite sides of which the ash sections 1^a are respectively glued. This I have found produces a better and more durable glued joint, and when the parts are adhesively joined under pressure, the softer wood 100 shapes itself to any irregularities in the surfaces of the side sections 1^a and gives a better and more durable glued connection. For some reason, not entirely clear to me, it has been found in practice to act as a buffer and 105 prevent any split in the flake.

In the manufacture of tennis rackets, it is customary to bend the ash frame and secure the parts in the manner shown in Fig. 1, before rounding and finishing the same. 110

Where the parts 1^b meet in the throat in a very acute angle, such as is formed when the portions 1^a are glued directly together without a filler strip, it is a difficult and costly operation to properly finish the open throat. The interposition of the filler strip produces sufficient space at the bottom of the throat to enable this to be readily accomplished, the throat terminating in a square abutment 10 formed by the end of the filler strip instead of an acute angle as heretofore.

As an additional precaution against splitting of the overlying handle flake, instead of running this down to a feather edge as 15 heretofore, I terminate it in an abrupt shoulder 1^c preferably extending transverse of the handle, which I cover with a finishing binding indicated at 6.

The flake termination may be of any abrupt formation, as for example, the rounded form, shown more in detail at 1^e, Fig. 6, or the beveled form shown at 1^f, Fig. 7.

Instead of having the filler strip 1^c of equal thickness throughout and confined to the parallel parts of the handle forming portions 1^a, it may be widened out or flared at its upper end as indicated at c, Fig. 8 to fit diverging portions of said handle members.

30 The filler strip may be of white pine, cedar, elm or any of the woods which are softer than the ash of which the frame is made.

Having thus described my invention, what 35 I claim is:

1. A tennis racket having a bow portion and integral handle portions, a crescent shaped strip secured to the inner face of the bow and bridging the throat, said crescent shaped piece having a reinforcing member

or portion on its outer face within the throat, contacting at its ends with the sides of the bow and leaving the throat open below it, and laminations at opposite sides of the racket overlying the crescent shaped piece, 45 substantially as described.

2. A tennis racket having a bow portion and integral handle portions of hard wood, a filler strip of softer wood lying between said handle portions and adhesively secured therebetween, a crescent shaped strip secured to the inner face of the bow and bridging the throat, said crescent shaped piece having a reinforcing member or portion on 50 its outer face within the throat, contacting at its ends with the sides of the bow and leaving the throat open below it, and laminations at opposite sides of the racket overlying the crescent shaped piece, the reinforcement and the arms of the bow, substantially as described.

3. A tennis racket having a bow portion and integral handle portions, a substantially 55 crescent shaped strip secured to the inner face of the bow and bridging the throat and leaving the throat open below the strip, a filler strip of softer material than the handle portions to opposite faces of which filler strip the handle portions are adhesively secured, the end of said filler strip forming a terminus for the open throat.

4. A tennis racket according to claim 2 provided with flakes overlapping and secured to opposite sides of the connected 75 handle portions and filler strip, said flakes terminating in abrupt shoulders spaced some distance from the bottom of the open throat.

In testimony whereof I affix my signature.
MILTON B. REACH.
